UNITED STATES PATENT OFFICE.

WILLIAM CHARLES CUNNINGHAM, OF NEW YORK, N. Y., ASSIGNOR TO ADAMS-
WILLIAMS MFG. CORPORATION, OF NEW YORK, N. Y., A CORPORATION OF
NEW YORK.

AUTOMOBILE-BODY CONSTRUCTION.

1,377,167.

Specification of Letters Patent.

Patented May 3, 1921.

Application filed September 28, 1919. Serial No. 326,502.

To all whom it may concern:

Be it known that I, WILLIAM C. CUNNINGHAM, a citizen of the United States, and a resident of New York, in the county of New York and State of New York, have invented certain new and useful Improvements in Automobile-Body Constructions, of which the following is a specification.

This invention is an improvement in that 10 type of automobile body construction in which readily movable panels are provided for closing the space between the upper edge of the body wall and the edge of the top to convert the vehicle into one of open or closed 15 type, at will. The invention relates particularly to the construction employed for rigidly but detachably securing the lower edge of the panel to the body. The main object of my invention is to provide a simple inexpensive device, efficient in operation, 20 inconspicuous in appearance, easy to operate, and readily installed, particularly on bodies of the open or touring car type.

The invention may be employed in connection with any or all of the panels but is 25 particularly useful for securing the panels to the swinging wall sections or doors of the body where the panel has no support or brace for its upper edge when the door is 30 open. It may of course be employed for the panels carried by the stationary wall sections where the upper edges of the panels may engage with or be secured to the rigid or folding top.

35 The usual automobile door includes a wood frame or body part and a sheet metal covering for at least the outer side and upper edge. The panel which I desire to secure to this upper edge and in the plane of the 40 door has a transparent body portion and a rigid frame presenting depending lugs in its own plane adapted to enter and be secured within corresponding sockets carried by or formed in the door. Various devices 45 and constructions have been proposed for receiving such lugs and rigidly clamping them and the panel in place.

By means of my improved construction, in its preferred form, I avoid the use of any 50 molding strip or other part upstanding from or projecting above the body edge; I cut away the frame of the door and correspondingly weaken it to the minimum extent; I

seat the panel directly on the door edge irrespective of the thickness or the cross sectional form of the latter; I utilize the sheet metal door covering as a reinforcement or backing for the clamping means; I provide a lug receiving socket which is comparatively inconspicuous when the panel is removed; and I secure the requisite strength without the use of parts projecting materially from or marring the appearance of the outer or inner surface of the door.

In the accompanying drawings I have 65 illustrated one embodiment of my invention.

In these drawings:

Figure 1 is a perspective view of a portion of a vehicle body with the door open and the panels in position.

Fig. 2 is a vertical section on a plane indicated by the line 2-2 of Fig. 4.

Fig. 3 is a transverse section on a plane indicated by the line 3-3 of Fig. 4, and

Figs. 4 and 5 are fragmentary elevations 75 of the inner and outer surface of the door in the vicinity of the clamping means.

I have illustrated my invention in connection with an automobile body having a stationary wall section 10 and a movable wall 80 section or door 11, each carrying a removable panel including a glass or other transparent body portion 12 and a rigid metal frame 13. The frame of each panel presents or includes a pair of depending lugs 14 rigid therewith 85 and in the same plane. Each wall section of the automobile body and particularly the movable wall section or door 11 includes a wood frame or body part 15 and a sheet metal covering or casing 16. This latter covers the 90 outer surface of the door frame and preferably the upper edge thereof as shown particularly in Fig. 2 and may or may not cover the inner surface.

As previously stated, my invention is particularly adapted for use in connection with automobile bodies which have previously been designed and built of the ordinary open or touring car type. In order to apply my invention thereto or incorporate it therein, I 95 cut into the upper edge of the frame a pair of apertures or sockets 17 designed to receive the lugs 14 of the corresponding panel. I also cut an aperture 18 through the wood frame from the inner surface to each socket. 100 For effectively clamping the lugs within the

sockets I provide a plate 19 upon the inner surface of the vehicle wall opposite to each socket. Each plate 19 has apertures therethrough for three threaded members and is 5 of a width somewhat greater than the width of the corresponding socket and lug 14 so that two of these threaded members may be disposed upon opposite sides of the socket for holding the plate 19 in position. This securing means is illustrated as including a pair of bolts 20 and corresponding internally threaded sockets 21 receiving the bolts. The bolts 20 are shown as having comparatively wide flat heads which engage with the outer sheet metal casing 16 but projecting beyond the latter to only a very slight extent. The coating threaded parts 16 extend through the plates 19 and receive the ends of the bolts. These also have comparatively wide flat 10 heads, although if desired, they may be countersunk into the plate 19. Either the member 20 or the member 21 has its head slotted, so that it may be rotated by means of a screw driver or other suitable tool while the other member is held against rotation and the plate 19 and the sheet metal casing 16 drawn toward each other and effectively clamped to hold the parts in position and prevent any 15 tendency of the plate 19 to pull away during the tightening of the lug clamp and to resist any tendency of the members 16 and 21 from separating.

The third threaded member which extends through the plate 19 is in the form of a 20 clamping screw 22, threaded in the plate 19, and disposed in the aperture 18 with its inner end movable into or out of the socket 17 to engage with and clamp the lug against the opposite side of the socket. Any suitable 25 means may be employed for tightening or loosening this clamping member. It may have an outer enlarged head whereby it may be readily tightened or loosened by grasping the end between the thumb and fingers or the 30 clamping member may terminate within or project to only a slight extent beyond the plate 19 and may have its outer end adapted to receive a key 23 shown in dotted lines in Fig. 2 or any other suitable member for 35 rotating the clamping member.

For giving the construction a more ornamental appearance, reinforcing the socket, and covering the edges of the casing around the upper end of the socket, I preferably 40 provide a socket liner or socket member 24. This may be made of metal of such size as to form a driving fit in the socket and have a chamber receiving the lug with a comparatively loose fit so that the panel may be readily placed in 45 position or removed when the clamping members 22 are loosened. It is not essential that the lower end of the socket liner be closed as such member may be of general tubular form open at the upper and lower ends. The upper 50 end is preferably flanged over to cover and

protect the edge of the sheet metal casing around the socket and to provide a bead reflecting water from the socket.

It will be noted that the wood frame of the door is reinforced at opposite sides of the 55 socket, the reinforcement on one surface being the outer sheet metal casing 16, and that on the inner surface, the plate 19. These reinforcing members are clamped together upon opposite sides of the socket so that the 60 wood is thoroughly reinforced and the application of pressure against the lug by the clamping member 22 will not tend to split away or break down the wood in which the socket is formed. It will also be noted that 65 no change whatever is necessary in the construction of the door in applying my improved construction thereto, except the cutting of the necessary apertures and that such 70 weakening as results from this cutting is more compensated for by the reinforcement provided by the parts added thereto. The device is applicable to doors of various 75 different thicknesses as the connecting members 20 and 21 provide for a considerable range of 80 adjustment and the clamping member 22 has a considerable range of movement due to the increased thickness of the plate at the center portion where the threaded aperture is formed therethrough. No great accuracy is required 85 in the exact positioning of the socket so far as its spacing between the opposite surfaces 90 of the wood frame is concerned as the clamping member will act efficiently irrespective of considerable variation in the distance between the socket and the plate 19. It will 95 also be noted that the socket may be formed parallel to the planes of the opposite surfaces of the door or may be cut in at any desired angle to give the panel a tilt inwardly or outwardly. Such a tilt is often desirable or 100 necessary to make the upper edge of the panel properly engage with the vehicle top when the door is closed. The parts of the 105 device are very simple in construction and they are very easily applied by comparatively unskilled workmen. The only parts visible from the outside of the car are the comparatively flat heads of the bolts 20 and 110 these may be painted or enameled the same 115 as the outer surface of the vehicle body so that they are comparatively inconspicuous. The plates 19 project inwardly to only a very slight extent and the socket liners do not detract from the trim appearance of the body 120 when the panel is removed.

Having thus described my invention what I claim as new and desire to secure by Letters Patent is:—

1. A vehicle body having a wall section including a wood frame and a sheet metal outer casing, a socket member in the upper edge of the frame and open at the top, a plate on the side of the wall section opposite to said sheet metal casing, connecting members extending 125 130

- through said frame upon opposite sides of said socket member and preventing separation of said plate and casing, and a clamping member carried by said plate and projecting 5 through the wall of said socket member.
2. A vehicle body having a wall section including a frame with a socket cut into the upper edge thereof and a sheet metal casing upon the outer side thereof, a plate on the 10 inner side of the wall section, connection members upon opposite sides of said socket and preventing separation of said plate and casing, and a clamping member carried by said plate and projecting into said socket.
- 15 3. A vehicle body having a wall section, including a wood frame, with a socket in the upper edge thereof, a plate on the inner side of the wall section opposite to said socket, means for securing said plate in position including two pairs of threaded members, one member of each pair having a comparatively flat head engaging with the outer side of the frame, and the other member of each pair engaging with said plate, and a clamping 20 member carried by said plate and having a portion projecting into said socket.
4. A vehicle body, having a wall section including a wood frame and a sheet metal outer casing, a tubular socket member inserted within the upper edge of the frame, 25 a plate upon the inner surface of said frame and secured to the latter upon opposite sides of said socket member, and a clamping screw carried by said plate and having one end projecting into said socket member. 35
5. A vehicle body wall section, including a wood frame and a sheet metal outer casing, and provided with a socket extending downwardly into the upper edge of the section and through said casing into said frame, a plate 40 secured to one outer surface of the section and anchored to the sheet metal casing upon the opposite surface, and a clamping member carried by said plate and projecting into said socket. 45
6. A vehicle body wall section, including a wood frame with a pair of sockets cut into the upper edge thereof, a sheet metal covering for the opposite surfaces and top of said frame, a pair of separate plates upon the 50 outer surface of the covering of the latter opposite said sockets and independently secured to said frame, a panel having a pair of lugs projecting into said sockets, and independent members carried by said plates for 55 engaging with said lugs to hold said panel in position.

Signed at New York city, in the county of New York and State of New York, this 17th day of September, A. D. 1919.

WILLIAM CHARLES CUNNINGHAM.
